ATTORNEY.

UNITED STATES PATENT OFFICE.

MICHAEL J. CALLAHAN, OF NEW YORK, N. Y.

DESIGN FOR A RADIATOR.

54,059.

Specification for Design.

Patented Nov. 4, 1919.

Application filed June 16, 1919. Serial No. 304,705. Term of patent 14 years.

To all whom it may concern:

Be it known that I, MICHAEL J. CALLAHAN, a citizen of the United States, residing in the borough of Manhattan, city, county, and State of New York, have invented a new, original, and ornamental Design for Radiators, of which the following is a specification, reference being had to the accompanying drawing, forming part thereof.

In the drawings, Figure 1 is an end elevation of the ornamental design for radiators; Fig. 2 is a front elevation of the radiator.

I claim:

The ornamental design for a radiator, as shown.

MICHAEL J. CALLAHAN.
